MAGAZINE REEL

Application filed July 21, 1926. Serial No. 123,850.

This invention relates to magazine reels and has for its object to provide a new and improved device of this description. The invention has other objects which are more particularly pointed out in the accompanying description.

Referring now to the drawings:

Figure 1 is a view showing a magazine reel embodying the invention; 10 Fig. 2 is an enlarged sectional view through the rotatable end of one of the roll supporting spindles.

Like numerals refer to like parts throughout the several figures.

15 In Fig. 1 I have shown a magazine reel used for delivering paper to printing presses. In this construction there is a shaft 1 mounted upon supports 2 and 3. Connected with the shaft 1 are arms 4 and 5 separated the 20 desired distance so that a reel of paper can be inserted between them. Connected with the arms are the spindles 6. Each spindle is provided with a spindle head 7 which is rotatably mounted thereon and which has the 25 roll engaging end 8 which projects into the opening in the roll so as to support the same. The spindle 6 is provided with a reduced portion 9. A series of rollers 10 is located between this reduced portion and the spindle 30 head 7.

The spindle has a second reduced portion 11 and there is a series of rollers 12 located between this reduced portion and the spindle head.

35 The end of the spindle is provided with a lock nut 13. The spindle head is provided with a screw cap 14. An oil hole 15 is provided for oiling the bearing surfaces. The spindle head is provided at the back with a 40 plate 16 which fits into a recess in the spindle head and which is held in place by the fastening devices 17. I prefer to provide an oil seal 18 which consists of some suitable packing inserted in an annular opening in the plate 16.

I claim:

1. A magazine reel comprising a rotatable shaft and supports therefor, arms connected with said shaft between which rolls of paper are supported, spindles connected with said support and projecting therefrom, a spindle head rotatably mounted upon the projecting portion of each spindle, said spindle head having a reduced portion which engages the roll of paper, and two sets of rollers on the 50 interior of said head which engage said spindle and which are at different distances radially from the axis of said spindle.

2. A magazine reel comprising a rotatable shaft and supports therefor, arms connected 60 with said shaft between which rolls of paper are supported, spindles connected with said support and projecting therefrom, a spindle head rotatably mounted upon the projecting portion of each spindle, said spindle head having a reduced portion which engages the roll of paper, the part of the spindle within said head being provided with a reduced portion, and rollers between said reduced portion of the spindle and said head said spindle being provided with a second reduced portion and rolls between said second reduced portion and said head.

3. A magazine reel comprising a rotatable shaft and supports therefor, arms connected 75 with said shaft between which rolls of paper are supported, spindles connected with said support, a spindle head rotatably mounted upon each spindle, said spindle head having a reduced portion which engages the device in connection with which the spindle is used, the part of the spindle within said head being provided with a reduced portion, and rollers between said reduced portion of the spindle and said head, said spindle being provided with a second reduced portion, rollers between said second reduced portion and said head, and means for preventing the movement of said rollers along said spindle.

4. A magazine reel comprising a rotatable 80

shaft, supports therefor, arms connected with said shaft between which rolls of paper are rotatably supported, spindles connected with said arms and projecting therefrom, a spindle 5 head rotatably mounted upon the projecting portion of each spindle, said spindle head having a reduced portion which projects into the hollow center of the roll of paper, rollers on the interior of said head which engage said 10 spindle, a removable end piece connected with the reduced portion of said spindle head and an oil seal at the other end of said spindle head.

15 Signed at Chicago county of Cook and State of Illinois, this 1st day of July, 1926.
JAMES E. RUST.
